MULTICOMPARTMENT BIRDHOUSE

James K. Bishop, Sr., Box 117A, Rte. 2,
Buffalo, Mo. 65622

Filed Apr. 19, 1973, Ser. No. 352,642

Term of patent 14 years

Int. Cl. D30—02

U.S. Cl. D30—3

FIG. 2.

FIG. 4.

FIG. 1.

FIG. 3.

FIG. 1 is a perspective view of a multicompartment birdhouse showing my new design;

FIG. 2 is a top plan view;

FIG. 3 is a side elevational view, the opposite side being identical to the view shown; and

FIG. 4 is a front elevational view, the rear view being identical to the front view as shown.

I claim:

The ornamental design for a multicompartment birdhouse, as shown and described.
